UNITED STATES PATENT OFFICE.

EMILE PIERRE ANTOINE ABRIC, OF PARIS, FRANCE.

RAILWAY SIGNALING.

1,385,295.

Specification of Letters Patent. Patented July 19, 1921.

Application filed September 23, 1918. Serial No. 255,317.

To all whom it may concern:

Be it known that I, EMILE PIERRE ANTOINE ABRIC, a citizen of the Republic of France, and residing at 48 Quai de la Rapée, Paris, France, have invented certain new and useful Improvements in Railway Signaling, of which the following is a specification.

The object of this invention is to provide an automatic block signal system which, although particularly applicable for use in subway or other underground systems, may also be used with surface lines, and which involves only the use of electrical connectors and lamps and avoids the use of mechanical devices, electromagnets, or other similar devices extensively used in block signal systems.

In my copending application Serial No. 250,596, filed August 19, 1918, a block signal system is disclosed in which a car or train entering a block automatically establishes an electrical circuit through a plurality of lamps including a control lamp ahead of the train, and one or more signal lamps in the rear of the train. My present invention also involves the use of a plurality of lamps including control lamps adapted to be lighted ahead of a train entering a certain block and signal lamps behind the train to warn succeeding trains, but the present invention involves a different arrangement of electrical circuits hereinafter to be fully disclosed.

Figure 1 of the accompanying drawings represents diagrammatically a block signal system in which the blocking and control signal lamps of the same section are in series;

Fig. 2 is a similar view in which the lamps are in parallel;

Fig. 3 is a view similar to Fig. 2, but showing an additional or safety lamp at each signal;

Fig. 4 is a cross section through a railroad track showing a portion of one embodiment of the invention incorporated therewith.

In the drawings the electric connector A is a continuous main running parallel to the track along its whole length, the trackway R itself constituting the return main. A conductor comprising insulated overlapping sections B' B² B³ B⁴, &c., is also parallel to the track R, the sections being preferably mounted on the cross ties between the rails, as illustrated in Fig. 4. Each of

these sections is coextensive with two block sections, but has no definite length, the length of the block sections being determined by the grade of the track, its curvature, the intended interval between trains, and the permissible speed.

At the ends of each block are located the signal lamps which comprise, referring to Figs. 1 and 2, control signals C, C', C² and C³ and block signals D D' D² and D³. In Fig. 3 additional signals E, E', E² and E³ are illustrated, which constitute safety signals adapted to be automatically illuminated when the lamps of the corresponding block signals have been destroyed. Each of the sections B, B', B², B³ and B⁴ is connected to the continuous main A. In Fig. 1 the connection includes a control lamp and blocking lamp in series. In Fig. 2 each section is connected in two places with the main A, one of said connections being through a control lamp and the other through a block signal lamp. The trackway as stated above, constitutes the return conductor and mounted upon each car of the line, one of which is indicated diagrammatically at F, is a suitable contact brush which bears against both sections of the interrupted conductor running parallel to the track. The brushes are electrically connected to the wheels of the car so that as the latter enters a block, connection is established between the mains A and R through two different connecting means. The brushes remain in contact with two sections of the sectional conductor so long as the car is traversing any given block, and at the end of the block the brushes pass over a gap between the ends of two of the sections, thus breaking the circuit through one set of lamps and creating a circuit through a new set.

In Fig. 1 the car F has established electrical connection between the trackway R and the main A through control lamp C and block signal lamp D' and also between the mains through control lamp C' and block signal lamp D². These lamps are, therefore, illuminated, warning a succeeding train or car such as F' that a car is in the second block ahead. In Fig. 2 the same effect is realized although the lamps are not connected in series, the car F having completed electrical circuit through control lamps C and C' and block signal lamps D' and D². The control lamps are for the pur-

pose of enabling the operator of the train, who is looking ahead, to see whether or not proper electrical connection has been made between the two mains R and A as his train 5 enters a block.

From the above it is apparent that the trains are separated by buffer sections, that is, when the signals are working properly, a train approaching a block signal in which 10 the lamp is illuminated will be warned that the preceding train is in the second block ahead and that caution should be exercised in proceeding, or that the train should be stopped entirely until the train ahead has 15 proceeded to a third block ahead.

Safety lamps E, E', E², E³ illustrated in Fig. 3, are illuminated when the block signal lamps D, D', D², D³ are destroyed, being connected in shunt with the circuit through 20 the block signal lamp. When it is seen that a safety lamp is illuminated instead of block signal lamp, the latter should be immediately replaced.

For electric railways the third wire or 25 trolley wire is used instead of the main A and, in case of the third wire the section conductor is preferably placed alongside the track adjacent the same. Where trolley wires are used the sectional conductor may 30 be placed close to it and suspended from the same supports in such manner that the conductors receive current through the trolley which will make contact with both trolley wire and the conductor. It is obvious also 35 that instead of utilizing only two lamps at the ends of each block, an increased number of lamps may be utilized and several buffer sections may be interposed thereby between each train and the train following.

40 Although the system is particularly applicable to subway systems, it may be utilized in connection with surface railways in which case the lamps are placed in a box which shields them from the daylight, and are visible only in certain directions, for instance in the direction of the approaching train.

The advantages of the invention will be 45 apparent from the above description. It is cheap to install in the first instance, there being no complicated mechanism and no moving parts other than the brush or brushes carried by the train, the maintenance cost is extremely low due to the simplicity of the system, and the danger of non-operation of signals is reduced to a minimum. Other advantages will also be apparent to those skilled in the art.

Having thus described the invention what 50 is claimed as new and desired to be obtained by Letters Patent is:

1. In block signal apparatus for railroads, in combination, parallel continuous electrical mains, conductors divided into insulated

overlapping sections, an electrical connection, including a signal lamp, between each section of said conductors and one of said mains, and means carried by a car for electrically connecting the other main simultaneously to one section of each of said conductors for the purpose set forth. 65

2. In block signal apparatus for railroads, in combination, parallel continuous electrical mains, conductors divided into insulated overlapping sections, a signal lamp at each end of each insulated section, an electrical connection, including one of said signal lamps, between each section of said conductors and one of said mains, and means carried by a car for electrically connecting the other main simultaneously to one section of 70 each of said conductors, for the purpose set forth. 75

3. In block signal apparatus for railroads, in combination, parallel continuous electrical mains, conductors divided into insulated overlapping sections, an electrical circuit, including a signal lamp and a control lamp, between each section of said conductors and one of said mains, and means carried by a car for electrically connecting the other main simultaneously to one section of each of 80 said conductors, for the purpose set forth. 85

4. In block signal apparatus for railroads, in combination, parallel continuous electrical mains, conductors divided into insulated overlapping sections each section being co-extensive with two blocks, a signal lamp at each end of each insulated section, each lamp being electrically connected to one of the insulated sections and to one of the mains, and means carried by a car for electrically connecting the other main simultaneously to one section of each of said conductors, for the purpose set forth. 90

5. In block signal apparatus for railroads, in combination, parallel continuous electrical mains, conductors divided into insulated overlapping sections, each section being co-extensive with two blocks, two signal lamps at each end of each block one of these two lamps being a block signal for one block and the other being the control signal for the block behind, electrical connecting means between each of the sections of the conductor and one of the mains, through a control and a signal lamp, and means carried by a car for electrically connecting the other main simultaneously to one section of each of said conductors, for the purpose set forth. 105

In testimony whereof I affix my signature 110 in presence of two witnesses.

EMILE PIERRE ANTOINE ABRIC.
